UNITED STATES PATENT OFFICE.

SHELLEY I. GLEASON, OF LOS ANGELES, CALIFORNIA, ASSIGNOR TO UNION TANK AND PIPE COMPANY, OF LOS ANGELES, CALIFORNIA, A CORPORATION OF CALIFORNIA.

VAPORIZER FOR VACUUM FUMIGATION.

Application filed May 9, 1925. Serial No. 29,109.

This invention relates to fumigating apparatus, and it particularly concerns a device for producing a toxicant which is of particular value in vacuum fumigation.

5 At the present time it is customary to practice vacuum fumigation by use of an apparatus which has an hermetically closed vessel in which articles to be fumigated are placed, this vessel being capable of resisting 10 atmospheric pressure. After the articles have been placed in the vessel, a vacuum is created therein, thus removing all of the air therefrom. The vapors of a toxicant are then introduced into the exhausted vessel. 15 These vapors are left to act, for a certain length of time, upon the bodies or articles to be fumigated. After this period of time has elapsed, depending upon the character of the articles being fumigated, the vapors are 20 exhausted from the vessel and air is allowed to enter. After the vessel is thoroughly washed with air, which washing comprises the drawing of clean air therethrough, the articles are removed therefrom completely 25 fumigated.

Hydrocyanic acid is used extensively as a toxicant in vacuum fumigation. This toxicant, however, is effective only on certain things. Hydrocyanic acid is of such a 30 character that it is absorbed by the things having a high moisture content. For this reason it is not entirely effective for fumigation purposes for all products due to the rapid vitiation of this gas by absorptions 35 into the water content. Further, hydrocyanic acid is very dangerous to handle. It is a deadly poison and people have been known to be killed thereby.

In an application entitled Process of mixing fumigating gases and composition of same, filed May 9, 1925, Serial No. 29,110, I presented to the Patent Office a new fumigating agent which is adapted especially for vacuum fumigation use. This toxicant of 40 my invention is composed of a lethal agent and a vehicle for carrying same. It is non-poisonous to human beings, which is a very important advantage over hydrocyanic acid. This renders the handling thereof easy. 45 Further, it is efficacious where hydrocyanic acid fails, that is to say, it is not absorbed by dampness and is therefore useful for fumigating many articles which cannot be fumigated by hydrocyanic acid. I desire to 50

use carbon-bisulphide as a lethal agent. 55 Carbon-bisulphide has no affinity for moisture and its effects are therefore not attenuated by the presence of water. Neither does it leave a disagreeable after-odor, this making it satisfactory for use on foodstuffs. 60

It is an object of my invention to provide an apparatus for producing a toxicant such as produced in the above referred to application. My apparatus comprises broadly a gasifying chamber, baffles in said 65 gasifying chamber and means for heating said gasifying chamber. A lethal agent is introduced into the chamber, where it is heated and where vaporization begins. A vehicle gas is passed through the lethal 70 agent in the gasifying chamber, carrying away therewith lethal agent vapors which combine with the vehicle to form a toxicant.

It is another object of this invention to provide an apparatus of this character, in 75 which the baffles may be easily cleaned. The apparatus is so constructed that the baffles may be readily removed and openings provided therein readily cleaned. It sometimes occurs that the substances used to produce 80 a toxicant of my invention have impurities which clog the orifices in the baffles. For example, I prefer to use carbon-bisulphide as a lethal agent. Impurities are sometimes carried in this composition in the form of 85 sulphur. This sulphur tends to collect and clog the openings of the baffle plates. This clogging, if occurring to any extent, entirely restrains the passage of fluid through the apparatus and causes considerable damage 90 by the building up of a high pressure in the gasifying chamber.

It is also an object of my invention to provide in an apparatus of the character mentioned a means for accurately measuring a 95 dose of lethal agent. This means is provided in the form of a cylinder, having a graduated tube associated therewith. The lethal agent is supplied to this cylinder, in which the proper dose is measured.

It is a still further object of my invention to provide an apparatus which is operated by the suction of the fumigating vessel of a fumigating apparatus, and therefore no special pumping means is necessary. I 100 accomplish this by connecting the pipes from the fumigating vessel to the gasifying chamber and to the graduated cylinder. 105

When it is desired to measure a dose of lethal agent, a valve is opened which subjects the cylinder to a vacuum, this drawing the lethal agent thereto. When the proper amount has been drawn into the cylinder, the valve just mentioned is closed. When it is desired to draw a lethal agent and vehicle into the gasifying chamber, a valve in the pipe connected thereto is opened, which subjects the gasifying chamber to a vacuum. This draws a lethal agent and the vehicle thereto. As the lethal agent, which is preferably in the form of a liquid, is vaporized, these lethal vapors are carried from the gasifying chamber by the vehicle, the combined gases forming a toxicant which is drawn into the fumigating vessel.

Other objects and the especial advantages of my invention will be emphasized in the following description.

Referring to the three sheets of drawings in which I illustrate a preferred form of my invention,

Fig. 1 is a diagrammatic view showing a complete fumigating apparatus employing a vaporizer apparatus of my invention.

Fig. 2 is an elevational view of a vaporizer of my invention.

Fig. 3 is an elevational view of my vaporizer taken substantially as indicated by the arrow 3 of Fig. 2.

Fig. 4 is a plan view of my vaporizer.

Fig. 5 is a vertical sectional view taken through the vaporizer clearly showing the gasifying chamber and baffle construction and other features thereof.

Fig. 6 is a cross section taken substantially as indicated by the line 6—6 of Fig. 5, this view clearly showing the web construction for supporting the gasifying tank of my invention.

Fig. 7 is a cross section taken substantially on the line 7—7 of Fig. 5, this view clearly showing the baffle arrangement of my invention.

Fig. 8 is a cross section taken on the line 8—8 of Fig. 5.

Fig. 9 is an enlarged fragmentary sectional view showing an injector arrangement employed in my invention.

With reference to Fig. 1 of the drawings, I show a fumigating vessel or treating tank 11, in which articles to be fumigated are placed. This vessel 11 has a cover 12 which is removable so as to provide admittance for articles to be fumigated and which is capable of securement so as to tightly seal the vessel 11. A vacuum pump 13 connects with the vessel 11 by means of a pipe 14 having a valve 10. When the vacuum pump 13 is operated, the interior of the vessel 11 is placed under a vacuum. A gauge 15 is secured in communication with the interior of the vessel 11, by which the condition of vacuum therein is indicated. An air inlet

pipe 16 is connected with the vessel 11, this pipe 16 having a valve 17 therein. The air pipe 16 is provided for the purpose of admitting air to the vessel 11 during the washing thereof, which will be explained later. A pipe 20 extends from the vessel 11 and connects to a vaporizer 25, which embodies the features of my invention.

With reference to the other figures of the drawings, the vaporizer 25 of my invention is provided in the form of an outer shell 26 having a tight bottom 27 and a removable top 28. The shell 26 is supported by a suitable standard 28. A heating liquid 29 is carried in the shell 26, this liquid being supplied thereto by means of an inlet pipe 30 having suitable valves 31 therein. The pipe 30 connects, as clearly shown in Fig. 2, with the upright portion of the standard 28. The level of the liquid 29 which is preferably water, is registered on a gauge glass 33 carried on the exterior of the shell 26, as clearly shown in Fig. 5. Electric heating elements 34 extend into the shell 26 for the purpose of heating the water 29.

An inner shell 35 providing a gasifying chamber 36 is supported inside the outer shell 26 by means of a supporting web 37, as clearly shown in Figs. 5 and 6. The web 37 has a central cylindrical opening 38 therethrough, through which the shell 35 is extended. The lower edge of a flange 39 which is secured at the upper end of the shell 26 engages an upper face of the web 37, thus supporting the inner shell 35 in place. The flange 39 carries a plurality of pivoted bolts 41 having wing nuts 42. These bolts and wing nuts are adapted to tightly clamp a cover 43 upon the open end of the shell 35.

Connected to the cover 43 and extending upwardly therefrom is a pipe 45. This pipe 45 extends through an opening 46 in the top 28 of the outer shell 26 and connects to a pipe 47 having a valve 50 by means of a union 48. The pipe 47 is connected with the pipe 20, which leads to the vessel 11 by means of a union 49. The pipe 47 also connects with a safety pipe 51 having a valve 52 therein, by means of a union 54.

A baffle arrangement 56, as clearly shown in Fig. 5, is carried in the gasifying chamber 36. This arrangement is provided in the form of a central supporting bar 57 having a handle 58 formed at the upper end thereof. Secured to the support 57 is a plurality of collars 59 which supports a series of baffle plates 61. These baffle plates 61 comprise flat plates which extend in a radial plane and completely close the gasifying chamber 36. However, these baffle plates 61 have openings 62 therethrough. The openings in the lowest baffle plate 61 are preferably about 1/4th inch in diameter, and the openings in the uppermost baffle plate 61 are preferably about 7/64ths inch in di-

ameter. Near the center of the gasifying chamber 36 I place sleeve baffles 65 and 66. The sleeve baffle 65 has a closed bottom 67 which is supported by one of the collars 59, 68 and the sleeve baffle 66 has a flange 70 by which it is secured to the upper edge of the sleeve baffle 65, as indicated at 71. In the bottom 67 of the baffle 65 holes 73 are provided. It will be noted from Fig. 7 that 10 these holes 73 are arranged about the exterior of the bottom plate of the sleeve baffle 66.

Secured at the lower end of the support 57 is a deflector 75 which rests on a bottom 15 76 of the inner shell 35. Openings 78 are provided in the deflector 75.

The baffle arrangement 56 is removable. This feature however will be explained later.

A measuring cylinder 85 is secured to the 20 side of the outer shell 26 by suitable brackets 81. The measuring cylinder 85, as clearly shown in Figs. 2 and 3, has a graduated tube 87 extending along the side thereof, this tube being connected to the lower end of the 25 cylinder 85 by a fitting 88 having a valve 89 and being connected to the upper end of the cylinder 85 by a fitting 91 having a valve 92. This graduate-tube 87 is provided with graduations 93.

From the lower end of the cylinder 85 there extends a pipe 94 having a cross fitting 95 connected thereto. Extending from one leg of the cross 95 is a pipe 96 having a valve 97, this pipe 96 extending upwardly, 30 as shown, and connects by means of a union 99 to a pipe 100. The pipe 100 is connected to a pipe 101 by means of a union 102. The pipe 101 extends to the interior of the shell 26, passing through an opening 103 in the 35 top 28. This pipe 101 extends to a point near the bottom of the shell 26 and connects to an injector 105. As shown in Fig. 9, the pipe 101 connects with a nozzle 106 of the injector 105, this nozzle being situated inside 40 the body 107 of the injector 105. Also connected with the cross 95 is a lethal agent inlet pipe 108 having a valve 109. A drain pipe 111 is connected with the remaining leg of the cross 95, this pipe 111 having a valve 45 112. The upper end of the cylinder 85 has a pipe 119 connected thereto, which extends to the safety pipe 51, this pipe 119 having a shut-off valve 120. Also connected to the 50 top of the cylinder 85 is a short pipe 121 opening to the atmosphere and having a valve 122.

A vehicle gas is introduced into the vaporizer 25 by means of a pipe 125 having a valve 126. This pipe 125 connects by means 55 of a union 127 to a short pipe 128. The pipe 128 connects to a pipe 129 by means of a union 130. The pipe 129, as clearly shown in Figs. 5, 8 and 9, extends through an opening 132 in the top 28 and extends to a point 60 near the bottom of the shell 26. As shown

in Fig. 9, the lower end of the pipe 129 connects with the interior of the body 107 of the injector 105.

In the operation of the fumigating apparatus shown in Fig. 1, the articles to be fumigated are placed in the vessel 11 and the door 12 is tightly secured in place to hermetically seal the interior of the vessel 11. The valve 50 in the pipe 47 which connects with the pipe 20 and the valve 17 in the air inlet pipe 16 are closed, and the valve 10 in the pipe 14 is opened. The vacuum pump 13 is then operated to evacuate the vessel 11. In this manner all of the air is withdrawn from the vessel 11 and a vacuum of substantially 28 inches is placed on the vessel. The valve 10 is then closed and the pump 13 shut down. The electric heating elements 33 are energized to heat the body of water 29 in the shell 26. This water is heated to a temperature of about 140° F., which is indicated on a thermometer 140. This temperature is suitable when using carbon-bisulphide as a lethal agent, this temperature being sufficient to vaporize this substance. The next 55 step is to measure the proper dose of lethal agent which is accomplished as follows. The valves 122, 109, 97 and 112 are closed. The valves 50 and 120 are then opened, which subjects the vaporizing chamber 36 60 and the interior of the measuring cylinder 85 to a vacuum. The valve 109 in the lethal agent inlet pipe 108 is opened. Carbon-bisulphide is then drawn into the measuring cylinder 85 by the vacuum placed thereupon. As the carbon-bisulphide liquid flows into the measuring cylinder, the level thereof is indicated on the graduated tube 89. When the proper amount is drawn into the cylinder, which is readily noted on the graduations 93 on the graduated tube 87, the valve 109 is closed and the valve 120 is also 65 closed.

A vehicle gas is then allowed to enter the gasifying chamber 36. This is accomplished 70 by opening the valve 126 in the pipe line 125, this valve 126 being opened only a slight degree, however. I prefer to use carbon-dioxide as a vehicle gas.

The lethal agent is then introduced into 75 the gasifying chamber 36. This is accomplished by opening the valve 122 which subjects the interior of the measuring cylinder 85 to atmospheric pressure. The valve 97 in the pipe line 96 is then opened and the 80 lethal agent is forced through this pipe by the pressure of the atmosphere on the top of the body of liquid in the cylinder 85. The lethal agent passes through the pipes 96, 100 and 101 to the injector 105. The liquid 85 passes from the nozzle 106 of the injector 105 with considerable force, impinging against the deflector 75 and being broken up and diffused thereby. When all of the liquid has 90 passed from the cylinder 85, which is dis- 95

cerned by observing the graduated tube 87, the valve 97 is closed. The lethal liquid forms a body in the lower portion of the gasifying chamber 36.

After all of the lethal agent has entered the gasifying chamber 36, the valve 126 is opened so as to allow a considerable flow of vehicle gas to pass into the gasifying chamber 36. The lethal agent is heated while in the gasifying chamber 36 and vaporization thereof commences. The vehicle gas in passing through this body picks up these vapors and carries them upwardly therewith, through the gasifying chamber 36, through the pipes 45, 47 and 20, into the vessel 11.

The baffle arrangement 56 is provided to prevent any liquid particles of the lethal agent from being carried with the vehicle gas. This is very effectively accomplished by passing the vehicle gas through the opening 62 in the baffle 61. This tends to rob the gas of any liquid particles. Further, by passing the vehicle gas around the cylindrical baffles 65 and 66, the freeing of liquid particles therefrom is assured. Should any liquid collect in the cylindrical baffle 65, it may drain therefrom through the openings 73. The openings 73, as previously described, are arranged to the exterior of the cylindrical baffle 66. They are thus arranged so that in case any liquid should be forced upwardly through these openings, it would not pass through the cylindrical baffle 66. This might occur due to excessive pressure in the lower part of the gasifying chamber.

This operation is carried on until the vessel 11 reaches atmospheric pressure which is indicated on the gauge 15. The lethal agent is vaporized entirely before the chamber 11 reaches atmospheric pressure, but the vehicle is passed through the vaporizer until this atmospheric pressure in the vessel 11 has been reached. At this time the valve 50 is again closed. The temperature in the chamber 11 is ordinarily sufficient to prevent an appreciable condensation of the lethal agent. The toxicant which is composed of the vehicle gas and lethal agent is left in the vessel 11 for a length of time, depending upon the character of the articles being fumigated. When this period has elapsed, the valve 10 in the pipe line 14 is opened and the vacuum pump 13 put into operation. This removes the toxicant from the vessel 11. The valve 17 in the air inlet pipe 16 is then opened and air is drawn into the vessel 11 by the vacuum pump 13, thoroughly washing same so as to assure the removing of all of the toxicant vapor. The cover 12 is then removed from place and the articles thoroughly fumigated are removed.

As previously mentioned, it is impossible to obtain an absolute vacuum of 30 inches. With standard equipment a vacuum of about

28 inches may be obtained. Considering that the vessel 11 has a capacity of 1000 cubic feet, producing a vacuum of 28 inches, leaves 1/15th of the capacity of the vessel therein, this amount being about 60 cubic feet. The amount of carbon-bisulphide which is generally used for a vessel of this capacity is 40 pounds, which forms a gas volume of about 200 cubic feet. This leaves a remainder of 740 cubic feet of space which must be filled by carbon-dioxide. The 40 pounds of carbon-bisulphide is measured in the measuring cylinder 85 and is then drawn into the gasifying chamber 36. The temperature and pressure of the gas in the fumigating chamber is substantially atmospheric.

The length of time that things are subjected to the toxicant varies according to the characters of these articles. For example, potatoes are subjected to the action of the toxicant for one hour and fifteen minutes, almonds for one hour and thirty minutes, and raisins for one hour.

When the toxicant or fumigating agent is withdrawn by the vacuum pump 13 from the vessel 11, 1/15th of the capacity of the vessel 11, or 60 cubic feet, is left therein. For this reason the vessel 11 is air-washed so that this remaining toxicant may be removed. The air washing of the vessel 11 is generally carried on for a period of about five minutes.

Carbon-bisulphide possesses qualities which are very favorable for vacuum fumigation. It smothers animal life, is a fat solvent and is somewhat poisonous. Carbon-bisulphide has one disadvantage, and that is that it is inflammable. In experimenting I used air as a vehicle. Much care had to be exerted to prevent an explosion due to the combining of oxygen in this air with the carbon-bisulphide. For this reason I use carbon-dioxide which is an inert gas and will not cause an explosion because there will be no chemical action thereof with the carbon-bisulphide.

As previously mentioned, I use only 200 cubic feet of carbon-bisulphide, whereas I use 740 cubic feet of carbon-dioxide. It is advantageous to use this excess of carbon-dioxide because it counteracts the presence of the 60 cubic feet of air left in the vessel 11. Without an excess of carbon-dioxide this air might combine with the carbon-bisulphide and result in an explosion.

It is not always possible to obtain an absolutely pure carbon-bisulphide, impurities being carried therein in the form of dissolved sulphur. This sulphur will collect on the baffles 61 and in time will clog the openings 62 therein. It is necessary at intervals to remove the baffle arrangement 56 to clean the openings 62 in the baffles 61. This is accomplished by detaching the unions 48, 49 and 54 which permits a removal of the pipe 47. It is also necessary

to detach the unions 127 and 130 to remove the portion of pipe 128 and to detach the unions 99 and 102 to remove the pipe 100. The top 28 of the shell 26 is then detached 5 and removed from place. This gives access to the interior of the shell 26 so that the wing nuts 42 may be loosened and the cover 43 removed from the inner shell 35. The baffle arrangement 56 is then removed by 10 lifting this arrangement upwardly out of the gasifying chamber 36. The handle 58 provides a convenient grip for the baffle arrangement.

Excessive pressures which might be created 15 in the lower portion of the gasifying chamber 36 by an expansion of the carbon-bisulphide, which might occur in the event of a clogging of the baffles, may be readily counteracted by opening the valve 52 in the 20 safety pipe 51, this allowing air to rush thereinto and to return the entire system to atmospheric pressure.

From the foregoing description it is obvious that the apparatus of my invention 25 operates to economically produce a fumigating gas or toxicant. The apparatus is operated automatically by the vacuum in the vessel 11. A desired dose of carbon-bisulphide or other lethal agent may be quickly 30 and accurately measured by the measuring arrangement of my invention. The baffles may be readily removed and easily cleaned. The measuring cylinder may be drained of any water or foreign substance by opening 35 the valve 112.

I claim as my invention:

1. In an apparatus of the character described, the combination of: walls forming a gasifying chamber; means for introducing 40 a lethal fluid into said gasifying chamber, said lethal fluid forming a body in the lower part of said gasifying chamber; means for passing a vehicle gas through said body of lethal fluid in said gasifying chamber, 45 said vehicle gas carrying gasified particles of said lethal fluid therewith; and means for conducting said lethal fluid and said vehicle gas from said gasifying chamber.

2. In an apparatus of the character described, the combination of: walls forming a gasifying chamber; means for introducing a lethal fluid into said gasifying chamber, 50 said lethal fluid forming a body in the lower part of said gasifying chamber; means for passing a vehicle gas through said body of 55 lethal fluid in said gasifying chamber, said vehicle gas carrying gasified particles of said lethal fluid therewith; means in said gasifying chamber for preventing fluid particles 60 of said lethal fluid from being carried with said vehicle gas; and means for conducting said lethal fluid and said vehicle gas from said gasifying chamber.

3. In an apparatus of the character described, the combination of: walls forming a

gasifying chamber; means for introducing a lethal fluid into said gasifying chamber, said 70 lethal fluid forming a body in the lower part of said gasifying chamber; means for passing a vehicle gas through said body of 75 lethal fluid in said gasifying chamber, said vehicle gas carrying gasified particles of said lethal fluid therewith; baffles situated in said gasifying chamber for preventing fluid particles of said lethal fluid from being carried with said vehicle gas; and means for conducting said lethal fluid and said vehicle gas from said gasifying chamber.

4. In an apparatus of the character described, the combination of: walls forming a 80 gasifying chamber; means for heating said gasifying chamber; means for introducing a lethal fluid into the lower end of said gasifying chamber, said lethal fluid forming a body in the lower part of said 85 gasifying chamber; means connected to the lower part of said gasifying chamber for passing a vehicle gas through said body of 90 lethal fluid in said gasifying chamber, said vehicle gas carrying gasified particles of 95 said lethal fluid therewith; baffles situated in said gasifying chamber for preventing fluid particles of said lethal fluid from being carried with said vehicle gas; and means for conducting said lethal fluid and said vehicle gas from said gasifying chamber.

5. In an apparatus of the character described, the combination of: walls forming a gasifying chamber; means for introducing a 100 lethal fluid into said gasifying chamber, 105 said lethal fluid forming a body in the lower part of said gasifying chamber; means for passing a vehicle gas through said body of 110 lethal fluid in said gasifying chamber, said vehicle gas carrying gasified particles of said 115 lethal fluid therewith; removable baffles situated in said gasifying chamber for preventing fluid particles of said lethal fluid from being carried with said vehicle gas, said removable baffles consisting of a support and baffle plates carried by said support short distances from each other, and means for 120 conducting said lethal fluid and said vehicle gas from said gasifying chamber.

6. In an apparatus of the character described, the combination of: walls forming a 125 gasifying chamber; means for measuring a dose of lethal fluid; means for introducing said lethal fluid into said gasifying chamber, said lethal fluid forming a body in the lower part of said gasifying chamber; means for passing a vehicle gas through said body of 130 lethal fluid in said gasifying chamber, said vehicle gas carrying gasified particles of said 135 lethal fluid therewith; and means for conducting said lethal fluid and said vehicle gas from said gasifying chamber.

7. In an apparatus of the character described, the combination of: walls forming a 140 gasifying chamber, said gasifying chamber

being under a vacuum; means for introducing a lethal fluid into said gasifying chamber; means for introducing a vehicle gas into said gasifying chamber; and means for conducting said lethal fluid and said vehicle gas from said gasifying chamber.

8. In an apparatus of the character described, the combination of: walls forming a gasifying chamber, said gasifying chamber being under a vacuum; means for introducing a lethal fluid into said gasifying chamber, said lethal fluid forming a body in the lower part of said gasifying chamber; means for passing a vehicle gas through said body of lethal fluid in said gasifying chamber, said vehicle gas carrying gasified particles of said lethal fluid therewith; and means for conducting said lethal fluid and said vehicle gas from said gasifying chamber.
9. In an apparatus of the class described, the combination of: an inner shell forming a gasifying chamber; an outer shell forming a heating chamber around said gasifying chamber, said heating chamber being arranged to contain a heating fluid; means for heating said heating fluid; a conduit connected to said gasifying chamber, said conduit being connected with a means for placing said gasifying chamber under a vacuum; means through which a lethal liquid is drawn into said gasifying chamber, said lethal liquid forming a body therein; and means through which a vehicle gas is drawn into said gasifying chamber, said vehicle gas being drawn through said body and through said conduit.
10. In an apparatus of the class described, the combination of: an inner shell forming a gasifying chamber; an outer shell forming a heating chamber around said gasifying

chamber, said heating chamber being arranged to contain a heating fluid; means for heating said heating fluid; a conduit connected to said gasifying chamber, said conduit being connected with a means for placing said gasifying chamber under a vacuum; means through which a lethal liquid is drawn into said gasifying chamber, said lethal liquid forming a body therein; a measure for measuring a dose of said lethal liquid before it is drawn into said gasifying chamber; and means through which a vehicle gas is drawn into said gasifying chamber, said vehicle gas being drawn through said body and through said conduit.

11. In an apparatus of the class described, the combination of: an inner shell forming a gasifying chamber; an outer shell forming a heating chamber around said gasifying chamber, said heating chamber being arranged to contain a heating fluid; means for heating said heating fluid; a conduit connected to said gasifying chamber, said conduit being connected with a means for placing said gasifying chamber under a vacuum; means through which a lethal liquid is drawn into said gasifying chamber, said lethal liquid forming a body therein; means through which a vehicle gas is drawn into said gasifying chamber, said vehicle gas being drawn through said body and through said conduit, said vehicle gas carrying particles of gasified lethal liquid therewith; and baffles arranged to prevent liquid particles from being carried by said vehicle gas.

In testimony whereof, I have hereunto set my hand at Los Angeles, California, this 4th day of May, 1925.

SHELLEY I. GLEASON.
